UNITED STATES PATENT OFFICE

1,923,999

NECKTIE HOLDER

Ferdinando Pesavento, Pittsburgh, Pa.

Application November 23, 1932
Serial No. 644,115

1 Claim. (Cl. 24—49)

This invention relates to necktie holders and has for the primary object, the provision of a device of the above stated character which may be easily and quickly applied to a necktie of the 5 four-in-hand type for retaining the latter in position on the wearer with the appearance of being tied in the usual manner so as to protect and prevent wear and soiling of the tie besides affording an ornamentation pleasing to the observer and becoming to the wearer.

With these and other objects in view this invention consists in certain novel features of construction, combination and arrangement of parts to be hereinafter more fully described and 15 claimed.

For a complete understanding of my invention, reference is to be had to the following description and accompanying drawing, in which

Figure 1 is an elevational view illustrating a 20 necktie holder applied to a necktie worn by a person.

Figure 2 is a vertical sectional view illustrating the holder applied to a necktie.

Figure 3 is a similar view with the holder removed from the tie.

Figure 4 is a front elevation illustrating the same.

Figure 5 is a similar view illustrating a modified ornamentation for the holder.

Figure 6 is a top plan view illustrating the device.

Figure 7 is a view showing a modified form of my invention applied to a necktie of the character worn by women.

Figure 8 is a plan view illustrating a holding ring.

Figure 9 is a plan view illustrating a holder.

Referring in detail to the drawing, the numeral 1 indicates a holder including a body 2 having a bore 3 tapering towards one end. The rear wall of the body is shorter than the front wall and the latter-named wall is provided with a projection of a desired shape or configuration to provide ornamentations to the body. The holder 1 is especially adapted for retaining a necktie 4 of the four-in-hand type in position upon the wearer. In use, the necktie 4 is passed through the bore 3 forming the usual neck loop in the necktie for encircling the neck of the wearer beneath the collar 5 of the shirt. The holder is then moved along the necktie until the upper end or the upper edge of the rear wall abuts the collar button of the collar, thereby effectively retaining the necktie in position with the appearance of being tied in the usual manner.

The body 2 besides giving the appearance of a knot in the tie of the four-in-hand type also provides a protection to the tie to prevent soiling of the latter by the chin of the wearer coming in contact with the tie. The holder besides having the foregoing described advantages relieves the tie of wear by eliminating the necessity of tying and untying the tie each time the latter is placed on and removed from the wearer.

Figures 4 and 5 show different shapes or designs of the ornamentation to the body and it is to be understood that other designs may be employed and also the body may be constructed of any material suitable for the purpose and which will also add to the artistic appearance of the device.

Referring to Figures 7 to 9, a holder 6 is provided especially adaptable for neckties worn by women and includes a ring-like element 7 adapted to be slipped over the ends of the tie and positioned adjacent the collar of the wearer with the holder applied to the necktie below the ring-like element 7. The holder 6 consists of a bar 8 having an ornamentation 9 and carrying at its end barrel shaped members 10 through which the ends of the tie may pass.

While I have shown and described the preferred embodiment of my invention, it will be understood that minor changes in construction, combination and arrangement of parts may be made without departing from the spirit and scope of my invention, as claimed.

Having described the invention, I claim:

A necktie holder comprising a body having a bore extending therethrough and tapering towards one end to receive and frictionally grip a necktie, said body including integrally connected front and rear walls of solid formation and said rear wall being shorter than the front wall and adapted to have one end thereof abut a collar button with the front wall projecting above the collar button.
